TYPEWRITING MACHINE

Filed Sept. 20, 1921

Patented July 3, 1923.

1,460,847

UNITED STATES PATENT OFFICE.

EDWARD B. HESS, OF MANHATTAN BEACH, NEW YORK, ASSIGNOR TO ROYAL TYPE-WRITER COMPANY, INC., OF NEW YORK, N. Y., A CORPORATION OF NEW YORK.

TYPEWRITING MACHINE.

Application filed September 20, 1921. Serial No. 501,893.

To all whom it may concern:

Be it known that I, EDWARD B. HESS, a citizen of the United States, residing at Manhattan Beach, in the county of Kings, New York, and State of New York, have invented certain new and useful Improvements in Typewriting Machines, of which the following is a specification.

This invention relates particularly to type actions for typewriting machines and especially to that class of type actions in which the type bars are actuated by the key levers through other levers interposed between the key levers and the type bars and operatively connected therewith. In one form of such type actions the interposed levers are in the form of bell-crank or two armed levers and they are connected with the rear portions of the key levers and with the rear ends or heels of the type bars. The construction in such type actions is such that when the keys are depressed the type bars are rapidly moved from positions of rest directly and without interruption to the printing point on the platen. In such machines the type bars strike the platen with considerable force and objectionable noise is produced which, according to my invention, is greatly decreased. In my U. S. Patent No. 1,390,708 of September 13, 1921, I have shown type actions in which provision is made for reducing the noise made by the impact of the type bars on the platen and therefore I do not herein claim broadly type actions which are so constructed as to reduce such noises, but according to my present invention such broader invention is adapted to mechanism of somewhat different construction from that shown in such patent.

In machines of the character before described, it is common to actuate the escapement mechanism by the type bars which operate directly upon the universal bar mechanism, while the type bars are being moved rapidly toward the platen. According to one part of my present invention the escapement is not operated during the initial portion of the movement of the type bars, but is operated during the latter part thereof during what is called in my prior patent the "momentum period," it being understood that the type bars are moved by a full depression of the keys to a point considerably in advance of the platen, the further movement of the type bars to the platen being

caused by the momentum of the type bars. The manner in which provision is made for reducing noise will be hereinafter more fully described, but briefly stated, the levers which are interposed between the key levers and the type bars are connected with the heels of the type bars by links or similar members in such manner that by the full depression of a key the associated type bar is moved only to a position considerably in advance of the platen and the type bar is moved to the printing point by the momentum of the type bar during which period the finger of the operator is usually on the key and the key makes a slight return movement which is resisted by the finger of the operator. It will further be understood that when the key is fully depressed certain parts of the mechanism interposed between the key levers and the type bars assume a toggle-locking or dead-center position which is an important feature of the construction.

In the accompanying drawings,

Figure 1 is a view, largely diagrammatic, of portions of a typewriting machine embodying my improvements, some parts being shown in side elevation and some in section and the position of some parts being slightly exaggerated for purposes of illustration;

Fig. 2 is a detail view illustrating the link connection between the heel of a type bar and the upper end of a bell-crank lever interposed between the type bar and a key lever. This figure of the drawing shows the parts in dead-center or toggle-locking position when the pivot points at opposite ends of the link are in a straight line with the pivot of the type bar. This figure also shows how the heel of the type bar makes contact with the universal bar at the commencement of the momentum period.

Fig. 3 is a view similar to Fig. 2, but illustrates the positions of the parts after they have passed the dead-center position during the momentum period, and this figure of the drawing also shows how the type bars engage the universal bar mechanism and operate it during the momentum period.

In Figure 1 of the drawings parts of a typewriter carriage are indicated at A, and B indicates a platen. C indicates a type bar segment, D a type bar guide and E parts of a ribbon guide. Escapement mechanism is indicated at F, a key lever at G and a type bar at H. The type bars normally lie hori-

zontally, their rear ends being pivoted to the segment at *c* and their front ends being supported by a cushioned rest I. The rear ends of the key levers are pivoted at *i* to a support J and the upward movement of the front portions of the key levers is arrested by a cushioned stop K. Each type bar H is formed with a heel having a rear portion *h*, which is connected by a spring L with a 10 spring support M and the heel of each type bar is formed with a cammed edge *h'* so shaped as to properly operate the universal bar mechanism, as hereinafter described. It will be observed that the pivots *c* of the type bars are arranged in rear of the front face of the segment and in fact within the body of the segment, being thus largely protected from dust, while the segment is so formed as to permit the heels of the type bars to operate freely during their excursion toward and from the platen. The springs L serve to return the type bars to their horizontal position of rest and to prevent vibration.

Each type bar is operated by devices interposed between it and an associated key lever, such devices being located immediately below the pivots of the type bars. These devices comprise a two-armed lever N and a link O. Each interposed lever N is pivoted 25 at *o* to the support J and its shorter arm is connected to the associated key lever by a slot and pin connection *o'*, while the longer arm of the lever is connected to the heel of the associated type bar by the link O. The 30 pivots *o* of the levers are in substantially the same vertical plane as the pivots of the type bars. The links O have pivotal connections at their opposite ends with the levers N and the heels of the type bars and when 35 the parts are in normal position the connections between the links and type bars are considerably in rear of the pivots of the type bars and at that time the angle between each lever N and each link O is substantially 40 a right angle so that when a lever N is operated there is a direct pull on the type bar during the initial movement of the key lever. At this time also the angle between a link and the associated type bar is approximately 45°.

The escapement mechanism is of substantially the same construction as that employed on the Royal Standard machines. The rocker plate R carries an arm *r*, 55 equipped with a roller *r'*, and this roller bears against an arm *s* of the universal bar mechanism, which latter is operated by the type bars. The universal bar mechanism comprises a frame S, pivoted at *t* to arms *t'*, 60 projecting downwards from a horizontally arranged shaft T. At its front end the frame carries a semi-circular part U with which the heels of the type bars engage during their excursion to the platen and the forward part of the frame S also carries a guide

finger *u*, projecting through the segment C. A spring *v* attached to the rocker plate R and to the arm *t'* serves to hold the universal bar mechanism in forward position and to return it to such position after being moved rearwardly. The forward movement of the universal bar mechanism is limited by an adjustable screw V.

Normally the heels of the type bar are out of contact with the universal bar, but as 75 soon as the type bars reach the position shown at X in Fig. 1, when the momentum period of the type bars commence at such time or thereafter, the cammed edges *h'* of the bars engage the universal bar, move it 80 rearwardly and operate the escapement.

When a key lever is depressed to its full extent, as indicated by dotted lines in Fig. 1, the interposed lever N, the link O and the type bar H are moved to the position shown by dotted lines in Fig. 1, the type bar being moved to a position indicated by dotted lines at X. When thus moved it will be observed by reference to Fig. 1 and also to Fig. 2 that the pivot points *y*, *y'*, 90 at opposite ends of the link O are in a direct line with the pivot *c* of the type bar, in other words in a dead-center or toggle-locking position, and there is no further downward movement of the key lever. 95 When in this position the type bar occupies the position shown at X. Its further movement to the platen is caused by the momentum of the type bar and not by the depression of the key lever, which latter, in fact, is never depressed further, but during the momentum period has a slight rising movement which is resisted to some extent by the finger of the operator. Experience has demonstrated that by this construction and 100 this operation the noise caused by impact of the type on the platen is very greatly reduced, and furthermore the universal bar is operated only during the momentum period 105 of the type bars.

It will be observed that the arm *s* of the universal bar mechanism is never out of contact with the escapement mechanism and thus noise which would otherwise be produced by the striking of the arm against the roller of the escapement mechanism is prevented.

The part J serves to support both the key levers and the interposed levers and the construction is such as to cover the pivots 115 of the key levers.

While I have particularly described certain details of construction shown in the accompanying drawings, it will be understood that I have shown only one way of embodying my improvements and many of the details of construction shown may be varied.

I claim as my invention:

1. In a typewriting machine the combi-

nation with the key levers and type bars of levers interposed between the rear portions of the key levers and the rear portions of the type bars which are operatively con-

5 nected with the key levers and have link connections with the type bars in the rear of their pivots, the points of connections of each link with its type bar and interposed lever being so related that a full depression
10 of the key lever moves them into a straight line with the type bar pivot, the type bar then being at a considerable distance from the platen and completing its movement by its own momentum.

15 2. In a typewriting machine the combination with the key levers and type bars of two-armed levers interposed between the rear portions of the key levers and the rear portions of the type bars and which have
20 their shorter arms operatively connected with the key levers and the longer arms of which have link connections with the type bars in the rear of the type bar pivots, the points of connection of each link with its
25 type bar and interposed lever being so related that a full depression of the key lever moves them into a straight line with the type bar pivot, the type bar then being at a considerable distance from the platen and
30 completing its movement by its own momentum.

3. In a typewriting machine the combination with the key levers and the type bars of levers interposed between the rear portions of the key levers and the rear portions of the type bars and which have toggle connections with the type bars, the points of connection of the toggles with the type bars and with the key levers being so related that each type bar is moved by the full depression of a key to a toggle-locking position in front of the platen and at such distance therefrom as to reduce noise during the further movement of a type bar about its pivot to the platen caused by the momentum of the type bar.

4. In a typewriting machine the combination with the key levers and the type bars of two-armed levers interposed between the rear portions of the key levers and the type bars which are operatively connected with the key levers and have link connections with the type bars in rear of and below the type bar pivots, the points of connection of the links with the interposed levers and the type bars being so related that each type bar is moved by the full depression of a key to a dead-center position in front of the platen and at such distance therefrom as to reduce noise during the further movement of the type bar about its pivot to the platen caused by the momentum of the type bar.

65 5. In a typewriting machine the combination with the key levers and the type bars of levers interposed between the rear por-

tions of the key levers and the rear portions of the type bars which are operatively connected with the key levers and have link connections with the type bars in the rear of their pivots, the points of connection of each link with its type bar and interposed lever being so related that a full depression of the key lever moves them into a straight line with the type bar pivot, escapement mechanism, and universal bar mechanism in constant engagement therewith and first engaged by the type bars when the key lever is fully depressed and operated by the type bar during its travel by momentum to the printing point. 70 75 80 85

6. In a typewriting machine the combination with the key levers and the type bars of levers interposed between the rear portions of the type bars and the rear portions of the key levers, and which have toggle connections with the type bars, the points of connections of the toggles with the type bars and with the key levers being so related that each type bar is moved by the full depression of a key to a toggle locking position in front of the platen and at such distance therefrom as to reduce noise during the further movement of a type bar about its pivot to the platen caused by the momentum of the type bar, escapement mechanism, and universal bar mechanism in constant engagement therewith and engaged by a type bar only at the full depression of the key and moved to operate the escapement mechanism during said momentum movement of the type bar.

7. In a typewriting machine the combination with the key levers and type bars both of which lie in substantially horizontal planes, of two-armed levers interposed between the type bars and the key levers, and links extending forwardly from the type bars at an acute angle thereto and connected to the upper ends of the two-armed levers, the points of connection of each link with its type bar and interposed lever being so related that a full depression of the key lever moves them into a straight line with the type bar pivot, the type bar then being at a considerable distance from the platen and completing its movement by its own momentum.

8. In a typewriting machine the combination with the key levers and type bars both of which lie in substantially horizontal planes, of two-armed levers interposed between the type bars and the key levers and having their lower and shorter arms connected to the key levers, and links extending at an acute angle to the type bars and connected to the longer arms of the interposed levers, the points of connection of each link with its type bar being so related that a full depression of the key lever moves them into a straight line with the type bar pivot, while

- the link extends at an obtuse angle to the type bar, the type bar then being at a considerable distance from the platen and completing its movement by its own momentum.
- 5 9. In a visible writing machine the combination with key levers having their finger pieces near the front of the machine and type bars whose free ends lie toward the front of the machine, of intermediate two 10 armed levers, the short arm of each two-armed lever being operatively connected to the key lever intermediate its length, and a link connection extending forwardly from
- the heel of each type bar and operatively connected to the upper and longer arm of the two-armed lever, the connection of the link to the lever and the link itself moving into a straight line with the type bar pivot upon a full depression of the key lever, the type bar then being at a considerable distance from the platen and completing its movement by its own momentum. 15 20

In testimony whereof I have hereunto subscribed my name.

EDWARD B. HESS.
